UNITED STATES PATENT OFFICE.

ISRAEL GITENSTEIN, OF NEW YORK, N. Y.

UNDERGARMENT.

1,105,901.

Specification of Letters Patent.

Patented Aug. 4, 1914.

Application filed July 11, 1913. Serial No. 778,572.

To all whom it may concern:

Be it known that I, ISRAEL GITENSTEIN, a citizen of the United States, and resident of New York, in the county of New York and State of New York, have invented certain new and useful Improvements in Undergarments, of which the following is a specification.

This invention relates to apparel and more especially to nether garments and consists of certain details in the construction of the seams at the lower sides of the garment adapted to enlarge and strengthen the seams so that garter clasps may be attached 15 to the same and the stockings or hose supported therefrom.

Further objects and details of the invention are more fully described in the following specification set forth in the claim and 20 illustrated in the accompanying drawings, wherein:

Figure 1 is a front view of a garment with the improvement applied thereto. Fig. 2 is an enlarged detail edge view with 25 a clasp attached. Fig. 3 is a fragment of one section of the garment material. Fig. 4 is a cross section through the edge of the garment. Fig. 5 is a similar view of a modified form.

Under garments have been made with hose supporters secured directly to same, but when washed the water soon destroys the rubber in the web of the supporter and rusts the metal parts of the latter. The 35 serious objection to attaching the clasp of a hose supporter to the material of the undergarment is that the same being of thin fabric there is little purchase for the clasp and the clasp is also likely to tear or stretch 40 the goods.

In order to overcome these difficulties the present invention consists in strengthening and reinforcing the garment along the seams so that the balance of the goods is not interfered with and the garment not made unsightly. By reinforcing the garment at the 45 seam the whole operation is performed and

the construction held together by one stitching.

In producing the reinforced seam above 50 referred to one of the sections 10 of the garment is cut in the usual manner with a straight vertical edge but the adjacent section 11 is cut with an extension 12 near its lower end. When the two sections are 55 placed together the extension 12 projecting beyond the edge of section 10 until it is folded over the latter edge when a seam is formed. The portion 12 thus forms an extra thickness or bulk on which the clasp 13 60 of a hose supporter may be caught and securely attached. The reinforced seam easily supports the strain of the hose and in no way endangers the tearing of the garment.

While it may be found most advantageous 65 to reinforce the seam of an undergarment as above described and shown, it is obvious that other means may be adopted to effect the same results as the use of a cord 14 within the seam as shown in Fig. 5. 70

In Fig. 3 the dotted line 15 represents the folding line while in other views 16 represents the stitching.

When the garment is to be washed the supporters are easily removed and the reinforcing in no way interferes with the laundering of the garment nor its general appearance. 75

What I claim as new is:

An undergarment comprising a pair of 80 drawers, each leg of said drawers provided with a seam on one side, the lower ends only of such seams provided with reinforcing means adapted to strengthen the same and afford supporting means for suspending garters therefrom. 85

Signed at New York in the county of New York and State of New York this 25th day of June.

ISRAEL GITENSTEIN.
